UNITED STATES PATENT OFFICE.

ELMER L. SCHUMACHER, OF SOUTHERIDGE, MASSACHUSETTS, ASSIGNOR TO AMERICAN OPTICAL COMPANY, OF SOUTHERIDGE, MASSACHUSETTS, A VOLUNTARY ASSOCIATION OF MASSACHUSETTS.

OPHTHALMIC MOUNTING.

1,306,779.

Specification of Letters Patent. Patented June 17, 1919.

Application filed November 29, 1917. Serial No. 204,593.

To all whom it may concern:

Be it known that I, ELMER L. SCHUMACHER, a citizen of the United States, residing at Southbridge, in the county of Worcester and State of Massachusetts, have invented certain new and useful Improvements in Ophthalmic Mountings, of which the following is a specification.

This invention relates to improvements in ophthalmic mountings and has particular reference to what is commonly known as the Windsor mounting; that is to say, a mounting made up of a combination of metallic and non-metallic parts.

One of the leading objects of the present invention is the provision in connection with a mounting of this character, of novel and improved means for readily and securely connecting the metallic and non-metallic portions of the construction.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a front elevation of a mounting embodying my improvements.

Fig. II represents an enlarged fragmentary perspective view of a portion thereof.

Fig. III represents a perspective view of the attaching clip employed in Fig. II.

Fig. IV represents a perspective view of a blank for a slightly modified form of attaching clip.

Fig. V represents an enlarged perspective view illustrating the use of one of these clips.

Fig. VI represents a sectional view illustrating the use of the clip shown in Fig. IV.

Fig. VII represents a perspective view illustrating the use of another modified form of my invention.

Fig. VIII represents a sectional view of another form thereof.

Fig. IX represents a fragmentary view illustrating the use of the form shown in Fig. VIII.

Fig. X represents a sectional view of another modification.

Fig. XI illustrates the use of a slightly different modification.

Referring specifically to the drawings, in Figs. II and III, I have shown the metallic frame 1, which has secured to it in the usual manner the end piece members 2, while encircling the frame 1 and extending entirely therearound, as should be understood by reference to Fig. I, is the non-metallic frame member 3. To retain the frame member 3 in position I preferably make use of the washer member 4 having the recess as at 5 to fit around the frame 1, and having a pair of upwardly extending fingers 6 provided with hooked terminal portions adapted to bite into the ends of the frame 3.

In use the frame 3 is cut to the proper length to fit around the outside of the frame 1 and has applied to each end the washer member 4 with its fingers 6 forced to bite into the zylonite and its hooked ends to firmly interlock therewith in the same manner as do the hooked ends illustrated in connection with Fig. VI, and suitable screws or other fastening devices 7 are then passed outward through the end pieces 2 to interengage with the threaded aperture 8 in the washer member or cap plate 4 to secure the plate 4 to the end piece and by drawing it tightly against the end piece to draw the frame 3 around the frame 1.

The form illustrated in Figs. IV to VI is substantially the same as the one just described, with the exception that the fingers 6 in place of being at the sides of the plate or washer 4 are placed one on the outer edge 9 and the opposite one at the center of the notch 5, one advantage of this construction being that the inner prong 6 will bend up into the groove adapted to receive the frame 1 and consequently will be entirely invisible, while the other prong or finger 6 will lie along the outside of the frame section 3 and will be practically invisible when the mounting is viewed from the front; a further advantage being that this outer prong will hold down the extreme end of the non-metallic frame and cause it to more snugly fit in place.

I have illustrated a further modification of my invention in connection with Fig. VII, in which the plate 4 has rising therefrom the standard member 9 terminating in the band or cross piece 10 adapted to be

bent around the non-metallic frame 3. It will thus be seen that the standard 9 preferably fitting in a slight groove in the outer face of the frame 3, holds it down at the bottom, while the portion 10 fitting around the non-metallic frame securely anchors the several parts together.

As a further modification of my invention I have illustrated in connection with Fig. 16 VIII a central terminally split prong member 11 as rising from the plate 4 and adapted to be centrally embedded in the terminal portion of the frame 3 to lock the plate 4 thereto.

15 Fig. X illustrates a form in which the plate or anchoring portion 12 fits against the inner face of the member 3, while a screw 13 passing through the plate 12 and into the frame 3 serves to lock the parts together.

20 Fig. XI illustrates another form in which in place of the plate 12 a prong or finger 14 is employed which grips into the portion 3, while the securing screw 7 extends upward centrally into the end of the member 3 and locks it against outward movement.

25 Thus in this form the plate and its prong 14 serve to hold the member 3 down toward the end piece, while this holding action is supplemented by the screw 7 which also locks

30 the end of the member 3 against outward movement away from engagement with the

prong 14. It will thus be seen that in connection with this form of my invention the fastening devices are all contained within the zylonite or non-metallic frame and are consequently invisible and at the same time the parts very securely held in place.

35 I claim:

1. A device of the character described including a holding member for a non-metallic rim, comprising a sheet metal stamping having a washer-like portion adapted to be secured to a metallic frame and having laterally extending portions adapted to be bent at right angles thereto to grippingly engage a non-metallic member.

2. A device of the character described including a holding member for non-metallic rims, comprising a sheet metal stamping having a washer-like portion adapted to be secured to a metallic frame and having laterally extending portions adapted to be bent at right angles thereto and spur members formed at the ends of the laterally extending portions to grippingly engage a non-metallic member.

40 In testimony whereof I have affixed my signature, in presence of two witnesses.

45 ELMER L. SCHUMACHER.

Witnesses:

H. E. COLEMAN,
A. S. CANN.
